[57] CLAIM

The ornamental design for a snow shovel head, as shown and described.

DESCRIPTION

FIG. 1 is a front elevational view of a snow shovel head showing my new design;

FIG. 2 is a right side elevational view thereof, the left side being a mirror image;

FIG. 3 is a top plan view thereof;

FIG. 4 is a bottom plan view thereof;

FIG. 5 is a rear elevational view thereof;

FIG. 6 is a rear elevational view of a second embodiment thereof, the only difference residing in the increased width and configuration of the angled support members;

FIG. 7 is a rear elevational view of a third embodiment thereof, the only difference residing in the increased width;

FIG. 8 is a rear perspective view of the embodiment of FIG. 1;

FIG. 9 is a rear perspective view of the embodiment of FIG. 6; and

FIG. 10 is a rear perspective view of the embodiment of FIG. 7.

The side of the snow shovel head opposite that shown in FIG. 2 is a mirror image of the side shown in FIG. 2. The characteristic feature of my design resides in the configuration of the rear side of the tool head.
